By George Bayard Jones, Mfg.

UNITED STATES PATENT OFFICE

GEORGE W. LORIMER, OF TROY, OHIO, ASSIGNOR TO BLACK PRODUCTS COMPANY, OF CHICAGO, ILLINOIS, A CORPORATION OF ILLINOIS

RECOIL PAD

Application filed January 3, 1929. Serial No. 330,113.

This invention relates to recoil pads adapted for use on the butts of guns to cushion the recoil thereof, although the invention may be employed in other relations.

5 The principal object of the invention is to provide a recoil pad of resilient material, the inherent cushioning action of which is augmented by the provision of openings therein, certain of which may be selectively plugged 10 to vary or localize the cushioning action of the pad to suit the desires of the individual.

Another object of the invention relates to the arrangement of the openings, as will be apparent from a consideration of the following specification and accompanying drawings, 15 wherein

Fig. 1 is a side elevation of an embodiment of the present invention, shown attached to the butt of a gun stock.

20 Fig. 2 is a broken perspective view of the same.

Fig. 3 is an elevation of the pad partly in section, and

25 Fig. 4 is a perspective view of a length of material which may be used for plugging certain of the openings in the pad.

In the drawings, 10 is the butt of a gun stock to which is attached, by means of screws 11, the recoil pad indicated generally by the 30 numeral 12. The pad preferably has a base 13 which may be formed of hard rubber on the inner surface of which are washers 14 through which the screws 11 or other fastening devices pass. The body 15 of a pad is 35 preferably formed of flexible or resilient material, such as rubber, and is provided with openings 16 through which a tool, such as a screw driver, may be inserted in attaching the pad to the gun stock. The base 13 and the resilient portion 15 are preferably secured 40 together by cementing or vulcanizing.

In the modification shown, two rows of 45 transverse openings 17 and 18 are provided which extend through the pad. The openings 18 are connected in pairs by arcuate slots 19 which also extend transversely of the pad. Alternate openings of the other row are adjacent the centers of the arcs of the curved 50 openings 19, as shown clearly in Fig. 1. This construction provides a pad having consider-

able cushioning effect, the inherent cushioning qualities of the material being augmented by the described openings.

In order to adapt the pad to the desires of the various users, I provide with each pad one or more lengths of plugging material for insertion in the openings 17, or if desired in the openings 18. A length of this material is illustrated in Fig. 4; and in Fig. 3 an opening is shown with a plug 20 in position. The 55 plug material is preferably flexible and compressible, such as rubber for example, and of a size to be frictionally retained in the openings. When the user desires to plug certain 60 openings to vary or localize the cushioning action of the pad, he inserts the plug in the proper openings and cuts the material off flush with the sides of the pad, as shown in Fig. 3. By this construction it is possible for 65 the flexibility or cushioning qualities of a pad to be varied to suit the desires of the individual.

Although I have shown and described a specific embodiment of the present improvements for the purpose of illustration, it will 70 be apparent that various changes may be made therein without departing from the spirit of the invention as defined in the appended claims.

What I claim is:

1. A pad formed of flexible material provided with a plurality of openings therethrough and plugs insertable in one or more of said openings for varying the cushioning 80 action of the pad.

2. A recoil pad formed of flexible material provided with a plurality of transverse openings therethrough to increase the cushioning qualities inherent in the material, and plugs insertable in one or more of said openings for 85 locally varying the cushioning action of the pad.

3. A recoil pad formed of flexible material provided with a plurality of transverse openings therethrough to increase the cushioning 90 quality inherent in the material, and resilient plugs insertable in one or more of said openings for locally varying the cushioning action 95 of the pad.

4. A recoil pad formed of flexible material 100

provided with a plurality of transverse openings therethrough to increase the cushioning quality inherent in the material, and resilient plugs insertable in one or more of said openings for locally varying the cushioning action of the pad, said plugs being of rubber and adapted for frictional retention in said openings.

5. A recoil pad formed of flexible material
10 provided with a plurality of rows of trans-
verse openings therethrough, the openings of
one row being arranged in pairs connected by
arcuate transverse slots each aligned with an
opening of another row, and means for plug-
15 ging one or more of said openings for varying
the cushioning action of the pad.

In testimony whereof, I have subscribed my
name.

GEORGE W. LORIMER.
